J. S. WINCRANTZ

SPIKE PULLER

Filed June 4, 1924

INVENTOR
John S. Muncandy,
Bynes, Tolson & Parmenter,
his Atty.

UNITED STATES PATENT OFFICE.

JOHN S. WINCRANTZ, OF WILKINSBURG, PENNSYLVANIA, ASSIGNOR TO VERONA TOOL WORKS, OF PITTSBURGH, PENNSYLVANIA, A CORPORATION OF PENNSYLVANIA.

SPIKE PULLER.

Application filed June 4, 1924. Serial No. 717,723.

To all whom it may concern:

Be it known that I, JOHN S. WINCRANTZ, a citizen of the United States, residing at Wilkinsburg, county of Allegheny, and 5 State of Pennsylvania, have invented a new and useful Improvement in Spike Pullers, of which the following is a full, clear, and exact description.

My invention relates to spike pullers, and 10 has for an object to provide an improved form of fulcrum member for the draw bar, whereby to obtain an increased leverage when starting a spike out of a tie.

Another object of the invention is to provide a fulcrum member having means on its 15 under side adapted to be embedded in a tie, which means is not liable to become clogged up with ice, dirt or the like on the upper surface of the tie.

20 The invention is illustrated in the accompanying drawings, in which,—

Figure 1 is a side elevation of the lower 25 end of a draw bar having one form of fulcrum member embodying my invention associated therewith, the draw bar being shown in its initial position upon being applied to a railway spike;

Figure 2 is a view similar to Figure 1 showing in full lines the position of the 30 parts when the draw bar is in position to begin raising the spike, and showing in dotted lines the position of the parts after the spike has been started out of the tie;

Figure 3 is a rear elevation of the parts 35 shown in Figure 2, and

Figure 4 is a detail view of a slightly modified form of fulcrum member.

Referring first to the form of the invention shown in Figures 1, 2 and 3, the number 2 designates the shank of a draw bar having a bifurcated claw 3 formed at its lower end, and also having a circularly curved enlargement 4 back of the claw, the curved surface 5 of this enlargement being 45 circular around a central point 6.

The circularly curved surface 5 merges into a flat under surface 7 which connects the curved surface 5 with the pointed end of the claw and at the point 6 an opening is 50 formed transversely through the bar to receive a bolt 8. This bolt supports two links 9 which are provided with slots 10 through which the bolt 8 passes, as shown in Figure 1. The links are pivotally connected at 55 their lower ends to a wedge-shaped fulcrum

member 11. The connection between the links and the fulcrum member is made by means of screw bolts 12 which extend into tapped openings in the sides of the fulcrum member. In the form of the invention 60 shown in these figures, the fulcrum member is provided at its rear end with a single relatively large tooth 13 projecting from the lower side of the fulcrum member and adapted to be embedded in a tie for holding 65 the fulcrum member in position during the pulling of a spike.

The spike puller may be provided with a grab hook, which, as shown, comprises a bar 14 having its rear end forked to provide two 70 arms 15 to straddle the draw bar. These arms are provided at their ends with openings to receive the bolt 8, whereby the grab hook is pivotally connected to the draw bar. The bar 14 has a member 16 slidably mounted 75 on the forward end portion thereof. This member is secured in position on the bar 14 by means of a wedge member 17 which extends through the same opening in the member 16 which receives the bar 14. 80

Figure 1 shows the manner in which the spike puller is first brought into engagement with a spike S which is shown embedded in a tie T adjacent to a rail R. The claw 3 is first placed astride of the spike, the grab hook, if used, being raised so as to pass over the top of the rail. The handle of the draw bar is then rocked forward into the position shown in full lines in Figure 2. The bar rocks on the point of its claw 3 90 and the fulcrum member 11 falls by its own weight into the position shown in Figure 2. In pulling a spike, the greatest effort is required in starting the spike out of the tie. With this in view, the fulcrum member is 95 formed with a flat upper surface 18, except at its forward end. The forward end portion of the fulcrum member is rounded and presents a curved surface 19 projecting slightly above the adjacent flat upper surface 18. In the full line position of the draw bar shown in Figure 2, this curved end surface 19 of the fulcrum member engages the flat under surface 7 of the draw bar. When the draw bar is rocked away from the 105 rail, it initially fulcrums on the curved end surface 19 of the fulcrum member until the draw bar reaches the dotted line position shown in Figure 2. Thereafter, the circularly curved surface 5 of the draw bar rolls 110

upon the flat upper surface 18 of the fulcrum member. It will be apparent at once that during the initial rocking movement of the draw bar, it is enabled to exert a 5 much greater leverage upon the spike to start it out of the tie than during the subsequent rocking movement of the bar, during which subsequent movement the curved surface 5 of the bar engages the flat surface 7 of the fulcrum member. This is of decided 10 advantage because of the fact that, as already stated, the greatest effort is required in starting the spike out of the tie.

It has heretofore been proposed to serrate 15 the lower surface of the fulcrum member to enable the latter to grip the tie, the serrations resulting in a series of small closely arranged teeth. With this construction, the teeth are liable to become clogged with ice, 20 dirt or the like on the upper surface of a tie, thereby preventing the fulcrum member from gripping the tie, so that, in pulling a spike, the fulcrum member is liable to slip. I propose to overcome this difficulty by providing the fulcrum member either with a 25 single relatively large tooth at its rear end, as shown in Figure 1, or with a series of relatively large teeth 20, as shown in Figure 4. With either form of construction, the 30 single tooth or the series of relatively large teeth will dig into the tie, irrespective of whether the same is covered with ice, dirt or the like, thus insuring the fulcrum member being held in place during the pulling of a 35 spike.

The slotted connection between the links 9 and the pivot bolt 8 causes the fulcrum member to act independently of the pivot bolt while a spike is being pulled. Therefore, 40 the load is supported wholly by the fulcrum member and not by the pivot bolt.

While I have shown and described two preferred embodiments of my invention, it will be understood that the invention is not limited to the exact form of fulcrum member shown in these embodiments thereof, as changes may be made in the constructions shown within the scope of the appended claims without departing from the spirit of 50 the invention.

I claim:

1. A spike puller, comprising a draw bar having an end portion adapted to engage under the head of a spike and having a bearing surface adjacent said end portion, and a fulcrum member adapted to be positioned beneath said bearing surface and having a raised bearing surface adjacent its forward end to provide a fulcrum for the bar in starting the spike, said bar being adapted to thereafter fulcrum on a portion of the upper surface of said fulcrum member back of said raised surface, substantially as described.

2. A spike puller, comprising a draw bar

having an end portion adapted to engage under the head of a spike and having a bearing surface adjacent said end portion, and a forwardly tapered fulcrum member adapted to be positioned beneath said bearing surface and having a raised bearing surface adjacent its forward end to provide a fulcrum for the bar in starting the spike, said bar being adapted to thereafter fulcrum on a portion of the upper surface of 70 said fulcrum member back of said raised surface, substantially as described.

3. A spike puller, comprising a draw bar having an end portion adapted to engage under the head of a spike and having a curved bearing surface behind said end portion, and a fulcrum member having a flat upper surface terminating adjacent the forward end of the member in a raised bearing surface, said raised bearing surface being 80 adapted to provide a fulcrum for the bar in starting the spike, the curved surface of the bar being adapted to thereafter cooperate with the flat upper surface of the fulcrum member in drawing the spike, substantially as described.

4. A spike puller, comprising a draw bar having an end portion adapted to engage under the head of a spike and having a curved bearing surface behind said end portion connected thereto by a straight under surface, and a fulcrum member having a flat upper surface adapted to cooperate with said curved bearing surface and having a raised surface at the forward end of said 95 flat surface adapted to provide a fulcrum for the bar in starting the spike, substantially as described.

5. A spike puller, comprising a draw bar having an end portion adapted to engage under the head of a spike and having a curved bearing surface behind said end portion connected therewith by a straight under surface, and a wedge-shaped fulcrum member pivotally connected to said bar and having a flat upper surface adapted to cooperate with said curved bearing surface, said flat surface terminating at the forward end of said member in a raised bearing surface 100 adapted to provide a fulcrum for the bar in starting the spike, substantially as described.

6. A fulcrum member for spike pullers, said fulcrum member having a flat upper surface terminating at the forward end of 105 said member in a raised bearing surface, substantially as described.

7. A fulcrum member for spike pullers, said member being wedge-shaped and having a raised bearing surface adjacent its 110 forward end, substantially as described.

8. A fulcrum member for spike pullers, said fulcrum member being of wedge shape and having a raised bearing surface adjacent its forward end, said member having 115

a relatively large tooth projecting from its lower surface and adapted to be embedded in a tie, substantially as described.

9. A fulcrum member for spike pullers, 5 said fulcrum member being of wedge shape and having a raised bearing surface adjacent its smaller end, said member having a

plurality of widely separated relatively large teeth projecting from its lower side, substantially as described. 10

In testimony whereof I have hereunto set my hand.

JOHN S. WINCRANTZ.
